Primary Examiner — Rebecca Tsehay*(74) Attorney, Agent, or Firm* — Mintz Levin Cohn Ferris Glovsky and Popeo, P.C.(57) **CLAIM**

The ornamental design for a vaporizer accessory, as shown and described.

DESCRIPTION

FIG. 1 is a top, front, and right side perspective view of a vaporizer accessory of our design;

FIG. 2 is a bottom, rear, and left perspective view thereof;

FIG. 3 is a top, front, and left perspective view thereof;

FIG. 4 is a bottom, rear, and right perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view thereof.

The dash-dash broken lines illustrate portions of the vaporizer accessory that form no part of the claimed design. The dash-dot broken lines illustrate boundary lines that form no part of the claimed design.
